Inventor
HARVEY J. MYERS

By Attorney

UNITED STATES PATENT OFFICE.

HARVEY J. MYERS, OF MINNEAPOLIS, MINNESOTA.

SANITARY DISPLAY COVER.

Application filed May 8, 1922. Serial No. 559,494.

To all whom it may concern:

Be it known that I, HARVEY J. MYERS, a citizen of the United States, residing at Minneapolis, in the county of Hennepin and State of Minnesota, have invented certain new and useful Improvements in Sanitary Display Covers, of which the following is a specification.

This invention relates to sanitary display covers for use on boxes, crates, barrels, pails or other containers in which is held and displayed edibles such as dried fruits, candies, ripe fruits, etc., and the main object is to provide a quickly and easily attachable and detachable cover having a large window through which the contents of the container may be seen, yet protected from rats, flies, cats or other insects or animals. Further objects will be disclosed in the course of the following specification and are illustrated in the accompanying drawing, in which:

Fig. 1 is a top view of a box equipped with my improved sanitary display cover.

Fig. 2 is a vertical section on the line 2—2 in Fig. 1.

Fig. 3 is a detail view of one section of the cover frame.

Fig. 4 is a perspective view of one of the hinge clamps, detached.

Referring to the drawing by reference characters 5 designates a container in which is packed the contents 6 to be shipped, displayed and sold. The cover which embodies my invention consists of a frame 7, in which is clamped a glass 8. The frame 7 consists of four pair of strips 9 all of which are rigidly secured together by rivets or screws 10. Each frame section comprises an upper and lower strip, each of which has an integral angular projection 11 at one end, which overlaps and is secured to the correspondingly opposite end of the adjacent strip, thus forming rigid connections at each corner of the frame.

The rear strip 9 is provided with a pair of slots 12 in which are hooked a pair of hinge clamping members 13, which clamp over the rear wall of the box (see Fig. 2). The members 13 are made of heavy spring material so that they will retain their proper position on the box, but may each be provided with a punched in tooth 14 which will insure the retention of the member in its proper place. The members 13 are further provided at their upper ends with upwardly projecting bearing portions 15, which en-

gage in the slots 12 so that the cover can be opened and closed by swinging thereon.

The cover may be supported in an open position by a bracket consisting of a pair of links 16 and 17, pivotally connected at 18. The link 16 is pivotally secured to the cover as at 19, while a short nail or screw 20 pivotally secures the link 17 to the box. The link 17 is further provided with a small lip 21 which engages in a notch 22 in the lever 16, to hold the bracket rigidly straight when the cover is open.

The cover is also provided near its rear end with a card holding member 23 having a pair of flanges 24 under which may be inserted a card or sign 25, designating the character or price of the contents in the box.

It is understood that suitable modifications may be made in this device, providing, however, that such modifications come within the spirit and scope of the appended claims.

Having now therefore fully shown and described my invention what I claim to be new and desire to protect by Letters Patent is:

1. A cover for containers consisting of a frame having a window therein, said frame having slots in the rear end thereof, hinge clamps adapted to engage said slots with their upper ends and to clamp on the container with their lower ends.

2. A display cover for containers, having slots in one end thereof, hinge members engageable in said slots, said members having downwardly extending clamping portions adapted to clamp onto the container.

3. A display cover for containers, having slots in one end thereof, hinge members engageable in said slots, said members having downwardly extending clamping portions adapted to clamp onto the container, each of said hinge members having a tooth in one of said clamping portions for engagement with the container.

4. In a device of the class described having a cover provided with slots in its rear end, means for hingedly securing the cover to a container consisting of a pair of clamping members adapted to be clamped onto the container, said clamping members having upwardly projecting integrally formed bearing portions engageable in said cover slots.

In testimony whereof I affix my signature.
HARVEY J. MYERS,
